(**) Term: **14 Years**

(57) **CLAIM**

(21) Appl. No.: **29/339,735**

The ornamental design for the keyed emergency stop cover, as shown and described.

(22) Filed: **Jul. 7, 2009**

DESCRIPTION

Related U.S. Application Data

(62) Division of application No. 29/318,169, filed on May 15, 2008, now Pat. No. Des. 596,144.

FIG. 1 is a perspective view of a keyed emergency stop cover, showing my new design;

(51) **LOC (9) Cl.** 13-03

FIG. 2 is a front view of the design of FIG. 1;

(52) **U.S. Cl.** **D13/171**

FIG. 3 is a rear view of the design of FIG. 1;

(58) **Field of Classification Search** D13/158,

D13/171, 173, 174; 200/51 LM, 334, 538; 318/445, 563; 361/170

See application file for complete search history.

FIG. 4 is a left side elevational view of the design of FIG. 1; FIG. 5 is a right side elevational view of the design of FIG. 1; and,

(56) **References Cited**

FIG. 6 is a top plan view of the design of FIG. 1.
